F. G. Fischer,

Attorney.

UNITED STATES PATENT OFFICE.

DANIEL N. DEAN, OF MIAMI, OKLAHOMA, ASSIGNOR OF ONE-HALF TO ERNEST E. PARKS, OF MIAMI, OKLAHOMA.

CHARGING DEVICE

Application filed September 1, 1923. Serial No. 660,523.

To all whom it may concern:

Be it known that I, DANIEL N. DEAN, a citizen of the United States, residing at Miami, in the county of Ottawa and State of Oklahoma, have invented certain new and useful Improvements in Charging Devices, of which the following is a specification.

My invention relates to devices for charging drill holes in mines and quarries with blasting powder, or other explosives, for the purpose of blasting out coal, ores, rock, etc., and my object is to provide a simple, inexpensive and efficient device of this character whereby said drill holes may be charged more quickly and at less expense than heretofore.

In the present method of charging drill holes, especially those extending in a horizontal or inclined plane, it is customary to form a sort of cartridge of a size to enter the hole by wrapping paper around the blasting powder. This operation takes up the miners' time, requires an expenditure of funds for purchase of the paper and results in more or less waste of powder when pouring the same into the paper wrapper. No paper is required in charging my device and the operation of filling said device with powder and transferring the same to the drill hole can be effected in much less time than is required in forming the cartridge above-mentioned.

In order that the invention may be fully understood, reference will now be had to the accompanying drawing, in which:

Fig. 1 is a longitudinal sectional view of the device containing a charge of powder and a fuse for exploding the same.

Fig. 2 is a cross section on line II—II of Fig. 1.

Fig. 3 is a detail perspective view of a plunger.

Fig. 4 is a detail perspective view of the receiver and its handle.

Fig. 5 is a broken detail of a modified form of plunger holding a fuse.

In carrying out the invention, I employ a trough-like receiver 2 of a size to enter a drill hole. Said receiver 2 is provided with a tubular handle 4 bent at its forward reduced end to form a tang 3 for engagement with the underside of the receiver 2, to which said tang 3 is riveted or otherwise firmly secured.

6 designates the plunger consisting of a

stem 8 and a head 10, which latter is fixed to the forward end of the former.

In practice, the plunger 6 is positioned with its head 10 in the rear portion of the receiver 2 and its stem 8 extending through the tubular handle 4, which latter also constitutes a guide for the plunger. The forward portion of the fuse A is then placed in the forward portion of the receiver 2 and extended along the outside of said receiver as shown by Fig. 1. The receiver 2 is then supplied with powder or other explosive B and inserted into the drill hole as far as possible. The receiver 2 is then drawn outwardly while the plunger 6 is held stationary for the purpose of forcing the explosive B and fuse A from said receiver 2 into the drill hole. After the explosive B and fuse A have been thus deposited in the drill hole the plunger 6 is withdrawn with said receiver 2 and the entrance to the drill hole is plugged up in the usual manner to add force to the explosion when the powder is ignited by the fuse A. The fuse A is of such length as to extend some distance out of the hole so that the person igniting it will have ample time to reach a safe position before the powder explodes.

The combined length of the receiver 2 and its handle 4 approximate the length of the drill holes to be charged, so that the explosive can be deposited against or near the inner terminals of said holes, and the length of the plunger handle 8 is greater than the combined length of the receiver 2 and its handle 4, so that a grip may be maintained on the rear end of said handle 8 when the receiver 2 is drawn outwardly to deposit the powder in the hole as above stated.

In the modified form disclosed by Fig. 5, the plunger 8^a is provided with a forwardly extending rod 10^a having a forked terminal at its forward end for holding the knotted end of the fuse a while the charge is being placed in the drill hole. When the plunger 8^a is withdrawn the forked rod passes out therewith and leaves the knotted end of the fuse a in the charge. One advantage of the modified form of plunger is that less fuse is required as the same does not have to be run around one end of the container.

From the foregoing description it is apparent that I have provided a charging device possessing the advantages above pointed out, and while I have shown and de-

scribed the preferred construction, combination and arrangement of parts, I reserve the right to make such changes as properly fall within the spirit and scope of the claim.

5 Having thus described my invention, what I claim and desire to secure by Letters Patent, is:

A device of the character described, consisting of a trough-like receiver, a tubular handle to said receiver, a plunger having a stem extending through said handle and a

head fixed to said stem and slideable in the receiver, and a rod extending forwardly from said plunger and terminating at its forward end in a fork, for the purpose specified.

In testimony whereof I affix my signature, in the presence of two witnesses.

DANIEL N. DEAN.
